(57) **CLAIM**

The ornamental design for medical equipment, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a left side view of a medical equipment showing our new design;

FIG. 1.2 is a rear view thereof;

FIG. 1.3 is a right side view thereof;

FIG. 1.4 is a top view thereof;

FIG. 1.5 is a bottom view thereof;

FIG. 1.6 is a front view thereof;

FIG. 1.7 is a perspective view thereof; and

FIGS. 3.1-3.3 are three different front views of the medical equipment creating an impression of an animated design, with the unseen views of the medical equipment of FIGS. 3.1-3.3 being identical to those of FIGS. 1.1-1.5.

The broken lines showing the medical equipment is for the purpose of illustrating portions of the medical equipment that form no part of the claimed design.

**1 Claim, 10 Drawing Sheets
